UNITED STATES PATENT OFFICE.

EMILE HERZ KLABER, OF LONDON, ENGLAND, ASSIGNOR TO AUGUSTUS DAVID KLABER, OF LONDON, ENGLAND.

MECHANICALLY-OPERATED MUSICAL INSTRUMENT.

No. 877,721.

Specification of Letters Patent.

Patented Jan. 28, 1908.

Application filed August 14, 1906. Serial No. 330,544.

To all whom it may concern:

Be it known that I, EMILE HERZ KLABER, a subject of the King of Great Britain and Ireland, and residing at 94 Regent street, in the 5 county of London, England, have invented certain new and useful Improvements in Mechanically-Operated Musical Instruments, of which the following is a specification.

The invention relates to mechanically operated musical instruments, such as pianos and the like, of the type in which a perforated music sheet passes over a tracker bar. It is desirable in such instruments that the attachment or fitting comprising the tracker 10 bar, music winding and re-winding devices and so forth should be disposed below the keyboard so as to avoid inconvenience when operating the piano by hand and for other reasons but although various devices of the 15 type indicated have been proposed these have commonly possessed the defect that the music sheet is not conveniently seen when in operation and thus the expression marks and other indications on the music cannot be 20 followed.

The object of the present invention is to overcome this difficulty by the provision of an attachment or device which although disposed in the desired position below the keyboard nevertheless allows the music to be 25 readily seen when the piano is operated.

The present invention thus consists in an attachment or device of the type indicated having as its main feature an arm or frame 30 pivoted or mounted below the keyboard of the instrument and adapted on the one hand to be swung out and so allow the music to be readily seen when the instrument is in operation, and on the other hand to be returned 35 or withdrawn below the keyboard when not required.

The invention preferably also comprises as subsidiary features a second pivoted swing arm or frame and a slidably mounted tracker 40 bar, the nature and functions of which will be hereinafter described.

Referring to the accompanying drawings which form part of the specification:—Figure 1 shows a front view of one form of the invention in its operative position; Fig. 2 being a corresponding end view and Fig. 3 an inverted plan, while Fig. 4, shows an end view of the device in its inoperative position.

In carrying the invention into effect ac-

cording to one form as applied by way of example to a piano, and as shown in the accompanying drawings, I provide a plate, *a*, adapted to be screwed or otherwise fastened below the keyboard, *b*, of the piano, and below this plate I slidably mount a second plate 60 *c*, carrying the tracker bar proper, *d*, provided with the usual tubular attachments, *e*, or the like. Slots, *f*, in the plate, *c*, are shown engaging with screw pins, *g*, in the plate, *a*, so as to allow the required sliding 65 motion, but any other suitable device may be substituted. I also mount on the plate, *a*, brackets, *h*¹, *h*², to which I pivot arms, *i*¹, *i*², rigidly connected by a bar, *k*, and carrying at their free ends the usual clip pivots, *m*¹, 70 *m*², for holding the music roll. Co-axially with these arms, *i*¹, *i*², but rotatable independently, I mount a second pair of arms, *n*¹, *n*², similarly connected by a bar, *o*, and carrying the take-up roller, *r*, on to which the 75 music sheet is wound when the piano is actuated. The arms, *n*¹, *n*², also carry small rollers, *s*¹, *s*², adapted to engage with spring clips, *t*¹, *t*², mounted on brackets *h*¹, *h*², and so hold the arms, *n*¹, *n*², in their operative 80 position.

The roller, *r*, is provided with the usual hook, *u*, or the like for the attachment of the music sheet and has rigidly secured to it the gear wheel, *v*, adapted to mesh with the 85 pinion, *w*, carried by the motion shaft, *x*. This shaft is operated from any suitable source of power by means for instance of the sprocket, *z*, attached to it and is moreover 90 slidably longitudinally in bearings provided for the purpose in the brackets, *h*¹, *h*².

Loose on the shaft, *x*, I provide a chain wheel, *2*, prevented from moving longitudinally by means of the bent plate, *3*, or the like secured to the bracket, *h*¹, and engaging 95 with the circumferential groove, *4*, formed on the hub portion of the chain wheel, *2*. The chain wheel, *2*, is connected by the chain, *5*, to a compound chain wheel, *6*, pivoted co-axially with the arms, *i*¹, *i*², and 100 *n*¹, *n*², and likewise rotatable independently, the chain wheel, *6*, being in turn connected by means of the chain, *7*, passing over suitable rollers, *8*, carried by the arm, *i*¹, to a corresponding wheel, *9*, secured to the clip 105 pivot, *m*¹.

To the plate, *a*, a lever, *10*, is pivotally secured at the point, *11*, and carries a project-

ing pin, 12, or the like adapted to engage between two collars, 13, 14, attached to the shaft, *x*. One of these collars, 13, carries a pin, 15, adapted to co-act with a corresponding pin, 16, fixed to the hub portion of the chain wheel, 2, operation of the lever, 10, thus enabling the chain wheel, 2, to be clutched to or unclutched from the motion shaft, *x*, as required, the pinion, *w*, being at the same time thrown out of or into gear with the roller wheel, *v*. A quick return motion of the music sheet on to the roller from which it has been unwound is thus secured.

The action of the complete device is as follows: If it is desired to operate the piano, the arms, *i¹*, *i²*, are swung out from their inoperative position below the keyboard, (see Fig. 4), into the operative position shown in Fig. 2, the position of the tracker bar being also changed as shown in the same figures. A roll of music is then inserted between the clips carried by the arms, *i¹*, *i²*, and the end of the roll is secured to the hook, *u*, on the roller, *r*; the arms, *n¹*, *n²*, carrying this roller, which have been swung out from below the keyboard for this latter purpose are then returned and secured by the spring clips, *t¹*, *t²*, this motion serving also to stretch the music sheet over the tracker bar into its operative position. The mechanism may then be set in operation and when desired, by actuating the lever, 10, may be reversed thus re-winding the music sheet at an increased speed on to the roller from which it has been drawn as explained above. The music roll may then be removed and the arms, *i¹*, *i²*, and the tracker bar returned to their inoperative position below the keyboard.

The usual tempo regulating devices and the like may also be arranged in conjunction with the device above described, so as to fold back below the keyboard when not required.

It will be seen that with the mechanism thus constructed the music-sheet is in plain view during the operation of playing the piano mechanically and the operator may readily see the expression marks thereon. Also when the mechanism for operating mechanically is not in use, it may be moved back under the keyboard so as to be not only out of view but also removed to such position that it will not be in the way of a person sitting at the piano to perform thereon manually. For this reason there is little danger of accidental injury to the mechanism. Further advantages characteristic of this construction result largely from mounting the tracker independently of the swinging frame; these are that shorter lengths of tubing leading to the tracker are required and there is less slack tubing when the tracker is in the retracted or inoperative position. By the provision of a second swinging frame for the take-up roll, the latter may be located

under the keyboard but can be swung out beyond the keyboard to facilitate attaching the end of a roll thereto.

Having now described my invention what I claim as new and desire to secure by Letters Patent is:—

1. The combination of a keyboard musical instrument, a frame pivotally mounted on the casing thereof below the keyboard, means on said frame for supporting a roll for a music-sheet, said frame being adapted to be swung about its pivots to carry said roll from a position below the keyboard to an operative position above the same, a tracker mounted on said casing below the keyboard independently of said frame, and a second roll for the music-sheet mounted on the side of said tracker opposite that of said first-named roll when the latter is in the operative position, substantially as described. 85

2. The combination of a keyboard musical instrument, a frame pivotally mounted on the casing thereof below the keyboard, means on said frame for supporting a roll for a music-sheet, said frame being adapted to be swung about its pivots to carry said roll from a position below the keyboard to an operative position above the same, a tracker mounted to slide upon said casing below the keyboard independently of said frame and a second roll for the music-sheet mounted on the side of said tracker opposite that of said first-named roll when the latter is in operative position, substantially as described. 90

3. The combination of a keyboard musical instrument, a frame pivotally mounted on the casing thereof below the keyboard, means on said frame for supporting a roll for a music-sheet, said frame being adapted to be swung about its pivots to carry said roll from a position below the keyboard to an operative position above the same, a tracker mounted on said casing below the keyboard independently of said frame, and a second roll for the music-sheet mounted below the keyboard of the instrument, substantially as described. 100

4. The combination of a keyboard musical instrument, a frame pivotally mounted on the casing thereof below the keyboard, means on said frame for supporting a roll for a music-sheet, said frame being adapted to be swung about its pivots to carry said roll from a position below the keyboard to an operative position above the same, a tracker mounted to slide upon the casing below the keyboard so that its edge projects beyond the keyboard and a second roll for the music-sheet mounted below the keyboard, substantially as described. 115 120 125

5. The combination of a keyboard musical instrument, two frames independently pivoted on the casing thereof below the keyboard, means on each of said frames for supporting a roll for a music-sheet and a tracker 130

to coact with the music-sheet on said rolls, substantially as described.

6. The combination of a keyboard musical instrument, two frames pivoted on the casing thereof below the keyboard and adapted to swing about the same axis, means on each of said frames for supporting a roll for a music-sheet and a tracker to coact with the music-sheet on said rolls, substantially as described.

7. The combination of a keyboard musical instrument, two frames independently pivoted on the casing thereof below the keyboard, means on each of said frames for supporting a roll for a music-sheet, each of said frames being adapted to be swung on its pivots to carry the roll thereon forward of the keyboard, and a tracker to coact with a music-sheet on said rolls, substantially as described.

8. The combination of a keyboard musical instrument, a frame pivotally mounted on the casing thereof below the keyboard, means on said frame for supporting a roll for a music-sheet, said frame being adapted to be swung about its pivots to carry said roll from a position below the keyboard to an operative position above the same, a tracker mounted on the casing below the keyboard, a second frame pivotally mounted on the casing below the keyboard, and means on said frame for supporting a roll for the music-sheet, substantially as described.

9. The combination of a keyboard musical instrument, a frame pivotally mounted on the casing thereof below the keyboard, means on said frame for supporting a roll for a music-sheet, said frame being adapted to be swung about its pivots to carry said roll from a position below the keyboard to an operative position above the same, a tracker mounted to slide upon the casing below the keyboard so that its edge projects beyond the keyboard, a second frame pivotally mounted on the casing below the keyboard and means on said frame for supporting a roll for the music-sheet, substantially as described.

10. The combination of a keyboard musical instrument, a tracker mounted below the keyboard and projecting beyond the forward edge thereof, means for supporting a roll for a music-sheet in operative position above the keyboard and means for supporting a second roll for the music-sheet in operative position under the keyboard, substantially as described.

11. The combination of a keyboard musical instrument, a tracker mounted below the keyboard and projecting beyond the forward edge thereof, a frame pivotally mounted below the keyboard, means thereon for supporting a roll for a music-sheet, said frame being adapted to be swung about its pivots to carry said roll to operative position above

the keyboard, and means for supporting a second roll for the music-sheet in operative position under the keyboard, substantially as described.

12. The combination of a keyboard musical instrument, a tracker mounted below the keyboard and projecting beyond the forward edge thereof, a frame pivotally mounted below the keyboard, means thereon for supporting a roll for a music-sheet, said frame being adapted to be swung about its pivots to carry said roll above the keyboard, a second frame pivotally mounted below the keyboard and means on said frame for supporting a roll for a music-sheet, substantially as described.

13. The combination of a keyboard musical instrument, a tracker mounted on the casing thereof below the keyboard with its edge projecting beyond the edge of the keyboard, means for supporting a roll for a music-sheet in operative position under the keyboard, and means for supporting a roll for the music-sheet above the tracker in such position that a music-sheet passing from one of said rolls to the other coacts with said tracker, substantially as described.

14. The combination of a keyboard musical instrument, a tracker mounted to slide on the casing thereof below the keyboard to and from a position in which it projects beyond the edge of the keyboard, means for supporting a roll for a music-sheet under the keyboard, and means for supporting a roll for the music-sheet above the tracker in such position that a music-sheet passing from one of said rolls to the other coacts with said tracker, substantially as described.

15. The combination of a keyboard musical instrument, a tracker mounted to slide on the casing thereof below the keyboard to and from a position in which it projects beyond the edge of the keyboard, means for supporting a roll for a music-sheet under the keyboard, a frame pivotally mounted below the keyboard, and means thereon for supporting a roll for the music-sheet, said frame being adapted to be swung about its pivots to carry the roll thereon above the tracker to such position that a music-sheet passing from one of said rolls to the other coacts with said tracker, substantially as described.

16. The combination of a keyboard musical instrument, two frames pivotally mounted below said keyboard one independently of the other, means on each of said frames for supporting a roll for a music-sheet, each of said frames being adapted to be swung about its pivots to and from an operative position, a clamp for holding one of said frames in the operative position, and a tracker coacting with a music-sheet passing from one of said rolls to the other, substantially as described.

17. In a mechanically-operated, keyboard,

musical instrument, the combination of a keyboard, two frames pivotally mounted below the same and adapted to be independently swung about their pivots to and from 5 operative positions, means on each of said frames for carrying a roll for a music-sheet, a gear for driving one of said rolls, a gear mounted on the casing of the instrument independently of said frames and means for 10 driving the same, and a clamping device for holding the parts in a position in which said gears are in mesh, substantially as described.

18. The combination of a keyboard musical instrument, a frame pivotally mounted 15 in the casing thereof below the keyboard, means on said frame for supporting a roll for a music-sheet, said frame being adapted to be swung about its pivots to carry said roll from a position below the keyboard to an op- 20 erative position above the same, means for driving a roll carried by said frame a tracker mounted on said casing below the keyboard independently of said frame, and a second roll for the music-sheet mounted on the side 25 of said tracker opposite that of said first-named roll when the latter is in the operative position, substantially as described.

19. The combination of a keyboard musical instrument, a tracker mounted on the 30 casing thereof below the keyboard with its edge projecting beyond the edge of the keyboard, a frame pivotally mounted below the keyboard, means thereon for supporting a roll for a music-sheet, said frame being adapted 35 to be swung about its pivots to carry said roll above the tracker, means for supporting a second roll for the music-sheet under the keyboard, and means for driving said last-named roll, substantially as described.

40 20. The combination of a keyboard musical instrument, a tracker mounted on the casing thereof below the keyboard with its edge projecting beyond the edge of the keyboard, means for supporting a roll for a 45 music-sheet in operative position under the keyboard, means for supporting a roll for the music-sheet in operative position above the tracker in such position that a music-sheet passing from one of said rolls to the other co- 50 acts with said tracker, and means for driving one or the other of said rolls, substantially as described.

21. The combination of a keyboard mu-

sical instrument, a tracker mounted to slide on the casing thereof below the keyboard to 55 and from a position in which it projects beyond the edge of the keyboard, means for supporting a roll for a music-sheet under the keyboard, a frame pivotally mounted below the keyboard, means thereon for supporting 60 a roll for the music sheet, said frame being adapted to be swung about its pivots to carry the roll thereon above the tracker to such position that a music-sheet passing from one of said rolls to the other coacts with said tracker, 65 and means for driving one or the other of said rolls, substantially as described.

22. The combination of a keyboard musical instrument, two frames pivoted on the casing thereof below the keyboard, means on 70 each of said frames for supporting a roll for a music-sheet, said frames being adapted to be swung about the same axis to carry the rolls thereon from operative to inoperative positions, means for driving one or the other of 75 said rolls when in the operative position, and a tracker to coact with a music-sheet passing from one of said rolls to the other, substantially as described.

23. The combination of a keyboard mu- 80 sical instrument, a tracker mounted in operative position upon the casing of the instrument, said tracker lying adjacent to the under surface of the keyboard of the instrument and being incapable of movement 85 above that surface, its operative edge projecting beyond the forward edge of the keyboard, and rolls for a music-sheet located in operative position one above said tracker and the other below and under said tracker 90 and keyboard, substantially as described.

24. The combination of a keyboard musical instrument, a tracker mounted to slide on the casing thereof below the keyboard to carry its operative edge beyond the forward 95 edge of the keyboard, and means for drawing a music-sheet across the operative edge of the tracker, substantially as described.

In testimony whereof I have signed my name to this specification in the presence of 100 two subscribing witnesses.
